UNITED STATES PATENT OFFICE.

OTIS R. NICKERSON, OF DREXEL, MISSOURI.

CATTLE-PUMP.

1,069,162.

Specification of Letters Patent.

Patented Aug. 5, 1913.

Application filed July 31, 1911. Serial No. 641,502.

To all whom it may concern:

Be it known that I, OTIS R. NICKERSON, a citizen of the United States, residing at Drexel, in the county of Cass, State of Missouri, have invented certain new and useful Improvements in Cattle-Pumps; and I do hereby declare the following to be a full, clear, and exact description of the invention, such as will enable others skilled in the art to which it appertains to make and use the same.

This invention relates to pumps and more especially to those commonly termed cattle pumps and the object of the invention is to provide a novel pumping apparatus of this character in which the water is raised from a well or cistern from air pressure created exterior of the well upon the approach of the stock to a water tank in connection with which the device operates.

A still further object of the invention is to provide an air tank adapted to receive air under pressure from a pump operated from a revolving platform upon which the stock approaches the tank so that the water will be lifted by the air in a siphon action.

A still further object of the invention is to provide means which will permit the escape of the air from the tank after the water tank has been filled so that continued operation of the pump will not cause the water tank to overflow.

With these and other objects in view, the invention consists of certain other combinations and arrangements of parts as will be hereinafter more fully described and claimed, it being a still further object to provide a device which will not be likely to get out of working order.

In the drawings:—Figure 1 is a vertical sectional view of a well or cistern with my improved cattle pump in elevation and applied thereto. Fig. 2 is a plan view thereof. Fig. 3 is a longitudinal sectional view of the revolving platform. Fig. 4 is a transverse sectional view thereof. Fig. 5 is a detail sectional view of the air tank and pump connected thereto, to more clearly illustrate the relief valve therein for permitting the escape of the air when the water tank is full and the pump is operated in the usual manner. Fig. 6 is a detail sectional view showing the use of a float valve to automatically control the discharge of air from the air cylinder for raising the water.

Referring to the accompanying draw-

ings, there is shown a well or cistern 10 which is provided with a top 11 adapted to receive an approximately U-shaped pipe structure having a supply portion 12 and an outlet portion 13, the bight portion 14 of the pipe terminating above the bottom of the well a short distance and extending into the water therein. Positioned slightly above the portion 14 and suitably secured to and communicating with the outlet portion 13 is an entrance connection 15, comprising an angular section of pipe having its horizontal portion secured to the section 13 and its vertical portion 70 extending downwardly to permit the proper entrance of water into the outlet portion. This portion 13 of the pipe structure terminates in a spout 16 adapted to discharge the water into a tank 17 which is preferably 75 circular in form and from which the stock are adapted to be watered in the usual manner. In order to supply water to the tank 17, the upper end of the pipe connection or supply pipe 12 terminates below the upper end of the discharge or outlet pipe 13 and is extended in a horizontal position as shown at 18 and connected to the upper end of an air tank 19, said air tank being positioned at any convenient point 80 adjacent to the water tank 17 and has a pipe connection 20 with a pump cylinder 21 suitably supported adjacent the lower end of the tank 19. This pump cylinder 21 has a piston 22 working therein and its piston rod 90 23 operates through one end of the cylinder and is eccentrically connected as shown at 24 to a crank disk 25.

In order to operate the pump I provide a revolving platform which is supported in an inclined position adjacent to the water tank and is suitably guarded if desired so that the cattle or stock must approach the tank upon the platform in order to drink. This platform comprises a series of angle bars 26 extending longitudinally of the platform and secured together at their ends, the said bars being spaced apart vertically and supported at their uppermost ends by uprights 28 while the lower ends of the bars are also spaced from the ground by uprights 29. The angle bars 26 are located adjacent the ends and central portions of the platform and the ends thereof are extended inwardly as shown at 30 to rotatably receive a pair of 105 shafts 31 and upon which a series of sprocket wheels 32 are mounted preferably

three at each end of the platform adjacent to the angle bars. Endless chains 33 are trained around said sprocket wheels and are secured together for simultaneous rotation by a plurality of transverse tread strips 34 which are secured to each of the chains. One of the uppermost uprights 28 of the platform rotatably carries the crank disk 25 adjacent its lower portion for the proper attachment of a pitman rod 23' which is connected to the piston and said crank disk has an endless chain 25' passed around it and the adjacent sprocket wheel 32' disposed thereabove, whereby when the animals approach the tank upon the platform, said platform will revolve causing the disk to rotate and operate the pump to supply air under pressure to the air tank.

A valve 35 is mounted upon the horizontal portion 18 of the air supply pipe 12 so as to control the passage of air from the air tank when created as above described, it being understood that when this valve is closed, the pump will be operative and in order to permit the escape of air from the air tank when the said valve is closed or the water tank is full, I provide an automatically actuated release valve 36 in the top of the air tank so as to open when the air within the tank has reached a predetermined pressure. When the valve 36 is open and the pump is operated, air will be forced through the supply pipe 12 and in passing through the pipe 13 will create a suction or siphon to draw water through the entrance connection 15 and discharge the same through the spout 16 into the water tank, it being understood that this operation takes place each time the platform is revolved by the approach of the stock to the water tank.

If desired, the entrance opening of the connection 15 may be provided with a suitable filter member 37 so as to purify the water in entering the discharge connection, and it will be evident from the foregoing description in connection with the accompanying drawings that I have provided an improved and durable form of pump which will be positive in operation in the manner specified. The pump may be constructed and applied to wells or other common sources of water supply, thereby rendering the same universal in use.

The release or relief valve 36 comprises a short pipe section 38 secured to the top of the air tank 19 by means of a flanged portion 40 and is provided with a diametrically arranged spider bar 41 adapted to receive the upper end of a valve stem 42 for vertical movement therein but to provide sufficient opening for the escape of the air from the tank upon opposite sides thereof, when it exceeds a predetermined pressure. A valve head 43 is carried at the lower end of the stem 42 and operates in a seat 44 formed as

an opening in the top of the tank 19 and said head is held in a seated position by means of a coiled spring 45 which is disposed between the bar 41 and a collar 46 upon the stem so as to normally exert downward pressure upon the valve, it being understood that the said spring may be regulated to permit opening of the valve to any desired pressure for the successful operation of the device.

I also provide the pump cylinder with an inwardly opening flap valve 47 to admit air to the cylinder on the suction stroke of the piston 22, and the pipe connection 20 is provided with a flap valve 48 mounted within the air tank 19 to permit the forcing of air into the said tank but prevent back pressure upon the piston from the air within the air tank.

As shown in Fig. 6 of the drawings, I provide means for automatically supplying air from the air tank to the pipe 18 and also to prevent the escape thereof when the water tank is full and for this purpose I provide a float 49 which is supported upon the water within the water tank 17 provided with a vertical standard 50 having a downturned end 51, the portion 50 being slidable in a guideway carried by the water tank to close the valve 52 when the tank is full and to permit opening of the valve through the medium of a spring arm 53 carried by the air tank, when the water falls below a certain level and thus permit water to be automatically supplied to the tank at all times.

I claim:

1. In a pump, a water tank, a U-shaped pipe connection having an entrance portion for water, an air pump, means for operating the air pump to supply air to the connection, a pair of valves controlling the exhaust and supply of air to the pump, whereby the air supplied to the connection will siphon a fluid into the outlet portion thereof and discharge the same into the tank, means to control the passage of air from the pump auxiliary to said first mentioned means and means to permit the escape of the air when the tank becomes full or the air has reached a predetermined pressure.

2. In a cattle pump, a pipe connection of approximately U-shape, one portion serving as a supply pipe for air and the other as a discharge connection having a spout, a tank adapted to receive the discharge from the spout, an angular entrance connection for the discharge portion positioned above the bight portion of the U-shaped section and extending below the same, a filter on said entrance connection to extend into a body of water, means operated by the approach of the cattle to the water tank to supply air to the air tank, automatic means to permit the escape of air from the tank upon a predetermined pressure.

- mined pressure being attained therein and a float operated valve controlling the supply of air from the air tank to the U-shaped pipe section.
- 5 3. In a cattle pump, a water tank, a siphon acting pipe section extending into a well and provided with a supply opening adapted to receive water therethrough by suction for discharging the same into the tank, an air reservoir connected near its upper end with one extremity of the siphon pipe, a reciprocating pump, the cylinder of which is provided with a pipe connection with the reservoir, an inwardly opening valve for the cylinder, a valve opening from the pipe connection to the reservoir, the first mentioned valve being adapted to open for supplying air to the cylinder adapted to close upon the opening of the latter valve for forcing the air into the reservoir, a relief valve for the top of the reservoir, said valve being spring actuated and permitting the escape of air from the reservoir when the water tank becomes full for cutting off the supply of air from the reservoir to the pipe section.
- 10 4. In a cattle pump, a revolving platform, a water tank, a siphon acting pipe section immersed in a body of water and disposed to discharge the same into the tank, a pump operated by movement of the platform, a reservoir having communication with the pump whereby operation of the latter will supply air to the reservoir, means to prevent back pressure of the air on the piston of the pump, an escape valve for the reservoir to permit the air to pass therefrom after it has attained a predetermined pressure, a connection between the first named pipe section and the reservoir, a float mounted in the tank, said float having a U-shaped arm depend-
- 15 ing exteriorly of the tank, a valve moving vertically in the last named connection and a spring arm connected to the valve and to the depending portion of the arm, said spring arm holding the valve normally open for the discharge of air from the reservoir into the pipe section, said float causing the valve to be closed against the action of the spring arm when the water in the tank has attained a predetermined level.
- 20 5. In a cattle pump, a water tank, a U-shaped pipe having a supply opening adapted to extend into a well, a reciprocating pump, a tank connected to the pump and U-shaped pipe and adapted to receive air from the pump, a revolving platform having connection with the piston of the pump for actuating the same to force air through the U-shaped pipe and siphon the water through the supply opening for discharging the same into the water tank, said platform comprising supporting legs holding the same in an inclined position, a plurality of upper and lower angle bars extending longitudinally of the platform and spaced apart centrally, the extremities of said bars being bent inwardly and secured together to form bearings, shafts journaled in said bearings, sprocket wheels carried by the shafts, chains engaged around said sprocket wheels, slats secured transversely to the chains to move simultaneously therewith and means to permit the escape of air from the air tank when the water tank becomes full.
- 25 In testimony whereof, I affix my signature, in presence of two witnesses.
